ILLUMINATED GAME DISPLAY PANEL OR THE LIKE

William G. Tregurtha, Monroeville, Pa. (371 Mathews
Road, Youngstown, Ohio 44512), and Harold J.
Greene, 750 Truesdale Road, Youngstown, Ohio
44511

Filed Mar. 2, 1967, Ser. No. 6,035

Term of patent 7 years

(Cl. D34—5)

The figure is a front plan view of the illuminated game display panel or the like.

The board is of conventional thickness and the rear is plain and unornamented.

We claim:

The ornamental design for an illuminated game display panel or the like, as shown and described.
